H. P. H. JONES

WREATH HOLDER

Filed Nov. 10, 1923

Inventor
Hugh P. H. Jones.

By Harry O. Schroeder
Attorney

UNITED STATES PATENT OFFICE.

HUGH P. H. JONES, OF OAKLAND, CALIFORNIA.

WREATH HOLDER.

Application filed November 10, 1923. Serial No. 673,935.

My invention is an improved hanger, particularly adapted to be used by funeral directors for hanging floral wreaths on a wall.

6 My invention is illustrated in the accompanying drawing which forms a part of this specification.

Referring to the drawing:

Figure 1 is a front view of my hanger.

10 Figure 2 is a side view of my hanger.

Figure 3 is a rear view of my hanger.

My hanger may be made in two sections 1 and 2, hinged together end to end at the rear by a hinge 3. The sections 1 and 2

15 may be made of sheet metal with side edge flanges 4 bent upon their rear side. The lower end 5 of the upper section 1 overlaps the upper end 6 of the lower section when the sections are unfolded into alignment.

20 My hanger may be made of sheet metal with side edge flanges 4 bent upon their rear side. The lower end 5 of the upper section 1 overlaps the upper end 6 of the lower section when the sections are unfolded into alignment.

25 My hanger may be made of sheet metal with side edge flanges 4 bent upon their rear side. The lower end 5 of the upper section 1 overlaps the upper end 6 of the lower section when the sections are unfolded into alignment.

30 My hanger may be made of sheet metal with side edge flanges 4 bent upon their rear side. The lower end 5 of the upper section 1 overlaps the upper end 6 of the lower section when the sections are unfolded into alignment.

35 My hanger may be made of sheet metal with side edge flanges 4 bent upon their rear side. The lower end 5 of the upper section 1 overlaps the upper end 6 of the lower section when the sections are unfolded into alignment.

40 When not in use, the sections 1 and 2 may be folded backwardly upon themselves on the hinge 3 so that they may be packed and carried from place to place.

A spacing arm 10 is hinged to the lower

section 2 and may be extended from the section or folded upon it as desired. When extended, arm 10 bears against the wall upon which the holder is hung, thus spacing the 45 lower end of the holder from the wall and holding the wreath in an inclined position for advantageous display. The overlapping end 5 prevents sections 1 and 2 from buckling on each other while in this position. 50

If it is desired to use a shorter hanger, due to limitations of space or other reason, section 2 may be folded upon section 1 and the holder used in the folded position.

Having described my invention, I claim: 55

1. A hanger comprising an upper rigid section, a hook thereon for suspending the hanger, a second hook extending forwardly from the upper section, a lower rigid section hinged to the upper section and provided 60 with a perforation therein, an overlapping end formed on the upper section and adapted to engage the lower section when the two sections are in alignment, and a pivoted spacing bar attached to the back of the 65 lower section.

2. A hanger comprising an upper section, a rearwardly extending hook attached thereto whereby the hanger may be suspended, a forwardly extending hook attached to the upper section whereby articles 70 may be suspended, a lower section hinged to the upper section, both said sections being formed of rigid material, an integral stop member on the upper section adapted to limit the relative angular movement of the two sections, said lower section being provided with a hole and a pivoted spacing bar attached to the back of the lower section. 75

In testimony whereof I affix my signature.

HUGH P. H. JONES.
